UNITED STATES PATENT OFFICE.

DAVID L. HOUGH, OF NEW YORK, N. Y.

TUNNELING APPARATUS.

SPECIFICATION forming part of Letters Patent No. 674,415, dated May 21, 1901.

Application filed August 25, 1899. Serial No. 728,445. (No model.)

To all whom it may concern:

Be it known that I, DAVID L. HOUGH, a citizen of the United States, residing in the borough of Manhattan, city of New York, State 5 of New York, have invented certain new and useful Improvements in Tunneling Apparatus, of which the following is a specification, reference being had to the accompanying drawings, forming a part hereof.

- 10 In driving subaqueous tunnels it has been usual heretofore to provide within the hood or shield of the tunnel a sufficient air-pressure to prevent the entrance of water through the material at the end of the tunnel through 15 which the tunnel is being driven and the breaking down of such material by the external pressure. It is well understood that the cost of such tunneling increases with the pressure which it is necessary to maintain 20 within the tunnel by reason of the difficulty of working in air under heavy pressure and that such work is very dangerous, particularly in tunnels of large diameter, by reason 25 of the great difference in the external pressures at the top and bottom of the tunnel, while the internal pressure must of necessity be the same at all points and will therefore be too great at the top of the tunnel or too small at the bottom.
- 30 It is the object of this invention to provide a tunneling apparatus which shall not be subject to the difficulties and dangers above referred to and shall require very little, if any, air-pressure within the tunnel above the normal atmospheric pressure.

35 In accordance with the invention the end of the hood or shield which is advanced as the work of excavation progresses is provided with a bulkhead, which prevents the 40 entrance of water or material within the tunnel and is provided with suitable tools to act upon the material in advance of the bulkhead, but operated by suitable means within the tunnel. Provision is also made for the 45 removal of the material which has been acted upon by such tools.

It will be evident that this invention can be embodied in many different forms of apparatus, as convenience in manufacture or 50 in use or the nature of the material through which the tunnel is driven or the conditions

under which the tunnel is driven may require. For purposes of explanation of the nature of the invention some of such forms of apparatus have been chosen for illustration in the accompanying drawings, and will be more fully described hereinafter. 55

In the drawings, Figure 1 is a view, partly in plan and partly in horizontal section, of one of such forms of apparatus, some of the 60 casing in rear of the hood or shield being represented. Fig. 2 is a vertical central section of a portion of the structure shown in Fig. 1. Fig. 3 is an inside elevation of the bulkhead shown in Figs. 1 and 2. Fig. 4 is a view 65 similar to Fig. 2, but showing a different form of the apparatus. Fig. 5 shows in front elevation a part of the outer bulkhead shown in Fig. 4 and a part of the inner bulkhead, and Fig. 6 is a detail view showing a portion of 70 the rear face of the inner bulkhead.

At A in Fig. 1 is represented a casing or lining which is put in place within the hood or shield B as the latter is advanced, as is usual in the ordinary methods of tunneling. 75 The particular construction of such casing or lining is not material to the present invention and may be of any usual or suitable character. The hood or shield B, which is advanced by means of hydraulic jacks b or otherwise as the tunneling progresses, may be of any desired shape in cross-section so far as concerns that form of the apparatus which is shown in Figs. 1, 2, and 3, although a circular cross-section is indicated. In or near 80 the forward end of the hood or shield is tightly secured a bulkhead C, which may be of any suitable construction, but is preferably cellular and sectional, as indicated in the drawings. The functions of this bulkhead in the 85 construction represented in Figs. 1, 2, and 3 are to prevent the entrance of water and of material within the hood or shield and to support suitable tools for operation upon the material in advance of the bulkhead, provision 90 being made for operating such tools from within the hood or shield and behind the bulkhead. 95

It is obvious that the tools and the means for supporting and operating the same will 100 be varied according to the nature of the material to be operated upon and other condi-

tions of their use. In the arrangement which has been chosen for illustration in Figs. 1, 2, and 3 of the drawings each tool D, having a drill-head or bur or other suitable head, as 5 the case may be, is represented as mounted in a sleeve or tube E, which has a universal bearing at e in a sleeve F. The sleeve or tube E may be provided with a suitable handle e', by means of which the tool can be moved about 10 in its universal bearing, and with a threaded hand-wheel e², which engages the threaded shank d of the tool D, so that the tool may be advanced or retired within its holder E, as may be desired. The shank of the tool is also 15 shown as connected by a flexible shaft b' with a suitable motor B', so that it may receive the necessary cutting motion; but it will be evident that any suitable means may be employed for operating the tool. As a convenient 20 means for permitting the complete withdrawal of a tool, so that it may be repaired or replaced by another more suitable to the work, the sleeve F is made movable in the bulkhead C, so that the outer end of the tool may be 25 withdrawn to the rear of the outer face of the bulkhead. Suitable screws f are shown as engaging a flange of the sleeve and as threaded into the inner wall of the bulkhead to force the sleeve home and retain it in position. The 30 outer end of the opening in the bulkhead through which the tool is extended is arranged to be closed when the tool is withdrawn to the position indicated in the upper right-hand corner of Fig. 1, as by means of a gate 35 c, which slides in suitable ways provided therefor. The gate is arranged to be operated from the inner side of the bulkhead and for this purpose may be provided with a rack c', engaged by a pinion c². The latter is carried 40 by a shaft c³, provided at its inner end with a hand-wheel c⁴.

The material which has been stirred up or broken up or otherwise reduced by the action of the tools or otherwise to small fragments 45 should be removed without requiring any opening through the bulkhead which would admit water and material within the hood or shield. For this purpose, as represented in the drawings, a suitable pump G may be provided 50 to force water through a suitable hose g and through the bulkhead into the space in front of the bulkhead, and another pump G' and hose g' may be similarly connected to the bulkhead to carry off the mingled water and 55 material.

In order that the face of the material operated upon may be examined from time to time, a tubular shell H may be arranged in the bulkhead to inclose suitable lamps h, the shell being 60 provided with openings h' to permit the passage of the light outward upon the face of the material or upon the tools. Within the shell H is disposed a second tube I, which is provided with an eyepiece i at one end and a 65 mirror i' and suitable sight-openings i² at the other end, thus permitting an examination of any of the tools or of any portion of the face

of the work. The tube I is rotatable within the tube H and may be provided with a hand-wheel i² to facilitate its movement.

The operation of the construction shown in Figs. 1, 2, and 3 of the drawings will be readily understood. When the hood or shield has been pressed forward by hydraulic jacks or other means as far as possible toward the face 70 of the work, the tools are extended through the bulkhead, are set in motion, and are so manipulated as to sweep over the whole face of the work. Meantime the pump G is forcing in water and the pump G' is carrying off 75 the mingled water and detritus. As fast as the condition of the face of the work will permit the hood or shield is advanced, the casting or lining of the tunnel being carried on with the advance of the hood or shield.

In the construction represented in Figs. 4 and 5 the tools D² are fixed to the outer face of the bulkhead, and the latter is rotated within the end of the hood or shield B. In order that the tool-carrier may be rotated regardless of the pressure at the end of the tunnel, while at the same time leakage into the tunnel may be prevented, the bulkhead is made double, the outer part or tool-carrier C' being rotatable and provided with rollers c⁵ 90 and c⁶ to bear against the hood or shield B and against the inner stationary part C² of the abutment. The carrier C' is secured to a tubular shaft C³, which is mounted in suitable bearings in the fixed abutment C² and in 95 a bracket B' and is provided with a gear C⁴, by which it may be driven from a suitable motor C⁵. Within the tubular shaft may be placed a pipe G², which opens through the face of the outer abutment or carrier C' in a 100 central position, so as to receive the detritus which is carried upward by the tools and is allowed to fall across the open end of the pipe, and at the other end is connected by means of an ordinary sleeve-joint g² with a suction-pump. (Not necessary to be shown in the drawings.) The pipe G³ within the tubular shaft is connected by a similar sleeve-joint with a force-pump, so that water may be forced into 105 the space between the two parts C' and C² of the abutment for the purpose of balancing the pressure against the outer face of the outer abutment or carrier as well as for furnishing the water which is mingled with the 110 detritus and carried off through the pipe G², the water escaping around the edge of the outer abutment or carrier, and thereby preventing the accumulation of material between the carrier and the hood or shield, which would 115 interfere with the rotation of the former.

It is desirable to provide for the withdrawal of the tools from time to time for the purpose of examination or repair, and for this purpose each tool is mounted upon a threaded shank d², which is larger in diameter than the head of the tool and is screwed into the carrier from its inner face. The inner or fixed abutment C² is provided with a series of apertures c⁷, which correspond in number and

position with each series of tools D², so that each tool can be withdrawn through the inner abutment. A bracket-arm D³ is arranged to be moved in a guide d³, parallel with the series 5 of holes c⁷, and to support a shaft D⁴, which is provided with a hand-wheel d⁴. The shaft D⁴ is formed at its end to engage the tool in line with it, is provided with a head d⁵, which fits snugly in the opening c⁷, and is also provided with a threaded portion d⁶, which is adapted to engage a threaded nut d⁷, carried by the arm D³. A gate c⁸ is provided for each hole c⁷ and is carried by a spindle c⁹, which is extended through the fixed abutment C². 15 When it is desired to remove a tool, the corresponding gate c⁸ is moved aside, and the shaft B⁴ is engaged with the tool and rotated until the tool has been screwed backward out of the carrier C'. At this time the threaded 20 portion d⁶ of the shaft D⁴ engages the nut d⁷, and the continued rotation of the shaft carries the tool backward into the opening c⁷ until its outer end has passed to the rear of the front face, so that the gate c⁸ can be closed, thus 25 preventing the entrance of water within the hood or shield. The head or flange d⁵ prevents the passage of water backward through the hole c⁷ while the shaft or key D⁴ is being inserted. The mode of operation of this form 30 of the apparatus will be readily understood. The rotation of the outer abutment or carrier disintegrates the material operated upon, and the detritus is carried off through the pipe G² in the manner already described. 35 It is to be understood that the forms of apparatus shown and described herein are merely two forms which may be used under

particular conditions and are illustrative of the general character of the invention, which is not to be restricted to the features of construction and arrangement heretofore described. 40

I claim as my invention—

1. A tunneling apparatus comprising a hood or shield, a bulkhead in said hood or shield 45 comprising an outer rotatable part or tool-carrier and an inner stationary part, means to rotate the outer part and means to supply water under pressure to the space between the outer and inner parts. 50

2. A tunneling apparatus comprising a hood or shield, a bulkhead in said hood or shield comprising an outer rotatable part or tool-carrier and an inner, stationary part, means to rotate the outer part, means to supply water under pressure to the space between the outer and the inner parts, and a pipe carried through the bulkhead for removal of the detritus from the space in front of the same. 55

3. A tunneling apparatus comprising a hood or shield, a bulkhead in said hood or shield comprising an outer rotatable part or tool-carrier and an inner stationary part, antifriction-rollers between the rotatable part and the stationary part, means to rotate the outer 60 part and means to supply water under pressure to the space between the outer and inner parts. 65

This specification signed and witnessed this 17th day of August, A. D. 1899.

DAVID L. HOUGH.
